UNITED STATES PATENT OFFICE.

ELIZABETH C. HARLLEE, OF RALEIGH, NORTH CAROLINA.

CONVERTIBLE CAR.

No. 914,270.

Specification of Letters Patent.

Patented March 2, 1909.

Application filed May 6, 1908. Serial No. 431,198.

To all whom it may concern:

Be it known that I, ELIZABETH C. HARLLEE, citizen of the United States, residing at Raleigh, in the county of Wake and State of North Carolina, have invented certain new and useful Improvements in Convertible Cars, of which the following is a specification.

This invention relates to means for converting a day coach into a sleeping car.

The object of the invention is to provide improved means of the character described.

An ancillary object of the invention is to provide an article of furniture which is adapted to provide a seat or chair or in conjunction with other of such articles, to form berths, the articles of furniture being convertible to be used in either capacity at pleasure.

Other ancillary objects of the invention will appear hereinafter.

In the accompanying drawings which illustrate the invention, Figure 1 is a side elevation of the improved article of furniture adjusted for use as a chair; Fig. 2 is a partial vertical section of the same; Fig. 3 is a side elevation of two chairs arranged to form upper and lower berths, the back of one of the chairs being partially broken away to show a section; Fig. 4 is a part of a transverse section through a car having the furniture arranged as in Fig. 3, the section being taken through the furniture on the vertical center line of Fig. 3; Fig. 5 is an enlarged perspective view of a portion of a chair. Fig. 6 is a view of a portion of the back and arm of a chair showing the details of a device for closing the interval between the arm and back, and, Fig. 7 is a section of the front portion of the portion of the chair back which forms the upper berth, showing a modified means for supporting the curtain for the lower berth.

Referring to the drawings, each of the articles of furniture comprises a base A, a seat B swiveled upon the base by any suitable means as the ball bearing 1, and a back C. The bases A are secured to the car floor D at suitable distances apart and preferably are arranged in longitudinal rows on the two sides of the car so that the arrangement, usual in parlor cars, of a row of seats along each side of the car, with an aisle between, is obtained.

In Fig. 4 a portion of the usual car roof E and one of the sides F is shown.

The seat portion B comprises a box like structure having the bottom 2, sides 3 and 4, and top 5, which box may be used for storage purposes. The upper side of the top of the box is provided with a cushion 6. Hinged to the top of the box at 7 is a portion 8 which may be extended out from the side of the seat in forming a berth as will be hereinafter referred to. The portion 8 has cushions 9 and 10 upon its two sides as shown. Extending rearwardly from the seat portion is a bracket 11 which is adapted to steady and support the back C when the chair is adjusted as shown in Figs. 1 and 2.

The back comprises a box like portion having sides 12 and 13 which extend forwardly from the back or bottom 14. To the sides 12 and 13, at their upper and forward portions, a swinging portion 15, is secured by means of pivots 16. When vertical, as shown in Figs. 1 and 2, this swinging portion provides a back rest for the chair and is provided on its front face with a cushion 17. When it is in horizontal position, as shown in Figs. 3 and 4, this swinging portion is adapted to form a portion of an upper berth. It will be seen that there is considerable clearance between the back 14 and the swinging portion 15, and in this clearance are arranged guides 18 and 19 within which slide weights as 20 each of which is connected by a cord, chain or other flexible connector 21, which passes over a pulley 22; with one end of the swinging portion 15, the weights referred to serving to counterbalance the weight of the swinging portion. At the top of the back is a lid 23 hinged at 24 so that it may occupy the horizontal position, as shown in Figs. 1 and 2, when the articles of furniture are being used as chairs, or may be thrown into a vertical position as shown in Figs. 3 and 4, when the articles of furniture are employed to form berths.

For the purpose of forming a partition between upper berths, there is hinged to the lid 23 a partition piece 50 which, when the article of furniture is adjusted for use as a chair, is folded down against the front of the back inside the cushion 17, the swinging portion 15 and the box within which it folds being recessed to receive the partition piece. To permit the swinging of the piece 50 into and out of folded position, the cushion 17 is hinged at 51 and may occupy the position as shown by full lines in Figs 1 and 2, or the upper portion may be swung into the position

as indicated by dotted lines in Fig. 1 to permit the partition piece to be moved outwardly.

In each article of furniture the back portion is secured to the seat portion so that it may turn with relation thereto, in other words, it is hinged thereto, the securing means also permitting the back portion to have a movement of translation with relation to the seat portion. The securing means shown for accomplishing this result comprises two links as 25 and 26 upon each side of the article of furniture, each of the links having an end pivoted to the seat portion and the link 26 having one end pivoted to the back portion. The link 25 is also pivoted to the back portion but this is accomplished by a pin-and-slot connection, this being shown as the slot 27 and the pin 28.

20 To provide arms for the articles of furniture there is hinged to the side of each seat an arm portion which may comprise vertical supports 29 and 30 hinged at 31 and 32 to the seat, the supports being connected at their 25 ends by a horizontal arm portion 33. This arm may be turned down out of the way, as shown in Fig. 1, or may be secured in raised position, as shown in Figs. 3 and 4. To the back portions are hinged blocks as 34 of approximately the same width as the arm portions 33. The details of the preferable form of these blocks is shown in Fig. 6 from which it will be seen that the blocks are formed of sheet metal and are at one end pivoted to the 35 seat back 17 while at the other end is a hook-shaped projection adapted to engage in a slot 65 in the arm portion 33 when the latter is raised. The purpose of these blocks is to prevent any portion of a person's anatomy 40 or clothes from becoming inserted and possibly caught between the arm and the back.

Hinged to the front of the seat portion of each of the articles of furniture is a bracket 35 which may be swung outwardly as shown in Figs. 3 and 4 or may be folded against the front of the seat as shown in Figs. 1 and 2. Secured between its sides to the bracket 35, by means of hinges 36, is a cross piece 37 which may be moved into a horizontal position across the top of the bracket 35, as shown in Figs. 3 and 4, it being secured in this position by a suitable catch 38', or it may be released from the catch and moved into a vertical position alongside the bracket 50 35 so that the whole can be swung compactly against the front of the seat as shown in Figs. 1 and 2. It will be observed that the upper part of the seat has an overhang so that a recess is provided for the reception of the bracket and this cross piece 37 so that a neat and compact arrangement is secured. The bracket with its cross piece may serve when extended, as a foot rest or as a seat for children when the article of furniture is em-

ployed as a chair or it may serve as a support 65 for the lower berth when the device is employed in that capacity.

Within the box like portion of the back of the article of furniture and near the upper end thereof and also near the outside when the articles of furniture are arranged to form berths, is hinged one end of a foldable curtain pole which may consist of sections 38, 39 and 40, one end of the section 40 being hinged to the back at 41 and the sections 38, 39 and 40 being hinged together. When the article of furniture is being used as a chair the sections of the curtain rod are folded alongside each other as indicated in Fig. 2 and are placed within the clearance behind the swinging portion 15, the lid 23 being closed down as shown in the figure last referred to. When it is desired to form berths the lids 23 are raised as shown in Figs. 3 and 4 and the curtain rods are raised into the 85 position as shown in those figures, the extreme ends of the rods abutting against each other and being secured in position by any suitable means as a sleeve 42 which may slide over the joint. This curtain rod provides a 90 means for hanging the curtain for concealing the interior of the upper berth.

The upper berth is formed by moving two swinging portions 15 of the articles of furniture into horizontal position as shown in Fig. 95 3, their abutting ends being secured by means of a spring catch 43 and they are further supported at their line of abutment by means of a bracket 44 hinged to the side of the car so that it may be swung beneath the 100 berths or may be folded against the side of the car out of the way. As a further support for the swinging portions, when forming an upper berth, each of the swinging portions 15 is provided upon each side with a leg as 45, 105 which legs are pivoted to the side of the swinging portion. These legs hang downwardly as shown when the swinging portions are in horizontal positions to form berths, the lower ends of the legs 45 entering sockets as 110 46 in the arm pieces 33 and are thereby supported and secured. Secured to the outer edges of the swinging portions 15 are rods as 47, serving as curtain poles for the lower berth, these rods entering the clearance within 115 the back of the articles of furniture when the swinging portions are folded within the same as shown in Fig. 2. Instead of the rods 47 supporting the curtains for the lower berths, the front edge may be concaved, as 120 shown in Fig. 7, and in this concavity may be placed buttons as 61 for supporting the curtains, the curtains being provided with button holes or rings to adapt them for engagement with the buttons 61.

As shown most clearly in Fig. 3 the portions 8 are turned on their hinges so as to extend between the seat portions of the coöp-

erating articles of furniture, to form the lower berth and the abutting ends of the portions 8 are secured in position by any suitable means as a spring catch 48 and the brackets 35 with their cross piece 37 are thrown outwardly beneath the portions 8 to further support them.

The articles of furniture being adjusted as shown in Figs. 1 and 2, they form swiveled chairs of the character now universally employed in parlor cars. If now it be desired to convert the car into a sleeping car the chairs are arranged in pairs, the chairs of a pair being so turned upon their swivels as to 15 face each other as shown in Fig. 3. The backs of the chairs may then be translated bodily upward with relation to the seat portions until the bottoms of the swinging portions 15 clear the seats, when the portions 15 20 may be swung upwardly upon their pivots 16 into a horizontal position as shown in Figs. 3 and 4. The counterweights relieve the effort necessary to raise the swinging portions and, these portions having been brought to 25 the horizontal position they are secured by a spring catch 43 and supported by a bracket 44 which is swung out beneath them. Also the legs 45 are secured in position, the arms 33 having been raised into vertical position 30 as shown. After the swinging portions have been swung out over the seat portions the backs are replaced in their brackets 11. The lids 23 and partition pieces 50 at the top of the chair backs having been raised as shown 35 in Figs. 3 and 4 and secured by any suitable means as a catch 62, the folded curtain poles are extended and their abutting ends are secured by a sleeve 42 and a curtain for concealing the upper berth may be hung thereon 40 in the usual manner. To form the lower berth the portions 8 of the chair seats are extended between the two seat portions of the pairs of chairs, as shown in Fig. 3, and secured by a spring catch 48, these portions 8 45 being further supported by the brackets 35 and their cross pieces 37 which are swung out beneath them. In reconverting the articles 50 of furniture into chairs the operations just described are inversely performed as will be obvious. To fill in the opening between the 55 chair box back and the chair seat which exists when the articles of furniture are in position to form berths, cushions 60 may be placed as indicated in Fig. 3, these cushions 2 being stored in the chair seat as shown in Fig. 55 when the articles of furniture are in use as chairs.

What I claim is,

1. In an article of furniture, the combination with a chair seat of a chair back comprising a swinging portion and counterbalancing weights for said swinging portion.

2. In an article of furniture, the combination with a base of a chair back swiveled thereon, and a chair seat, said chair back

comprising a swinging portion and counterbalancing weights therefor.

3. In an article of furniture, the combination with a chair seat and a chair back comprising a curtain pole. 70

4. In an article of furniture, the combination with a chair seat and a chair back comprising a foldable curtain pole.

5. In an article of furniture, the combination with a chair seat of a chair back, comprising a swinging portion and means for supporting a curtain secured to said swinging portion. 75

6. In an article of furniture, the combination with a chair seat of a chair back, said chair seat comprising an extensible portion and a bracket foldable against the side of said seat and adapted to be swung beneath said extensible portion to support the same. 80

7. The combination with a car, of articles 85 of furniture upon the floor thereof, each of said articles of furniture comprising a chair seat and a chair back, said articles of furniture being arranged in pairs and the chair back of each comprising a swinging portion, 90 said swinging portions being adapted to be moved into a horizontal position with their free ends adjacent, and a bracket foldable against the side of the car and adapted to extend beneath the abutting ends of said 95 swinging portions.

8. In an article of furniture, the combination with a chair seat of a chair back, said chair back comprising a swinging portion adapted to be swung from a vertical to a 100 horizontal position over said seat, pivoted links securing said back to said seat, one of said links having a pin-and-slot connection, and a bracket for supporting said back secured to said seat. 105

9. The combination with one article of furniture of another article of furniture, each of said articles of furniture comprising a chair seat and a chair back, each of said chair backs comprising a swinging portion and a curtain 110 pole, the said articles of furniture being adjustable so that the said swinging portions of said articles of furniture have their free ends adjacent when in the horizontal position and the ends of said curtain poles are 115 adjacent when extended.

10. In an article of furniture, the combination with a chair seat of a chair back, said chair seat comprising an extensible portion and a bracket foldable against the side of said seat and adapted to be swung beneath said extensible portion to support the same, said bracket comprising a cross piece movable into horizontal and vertical positions. 120

In testimony whereof I have affixed my 125 signature, in presence of two witnesses.

ELIZABETH C. HARLLEE.
